WALL TELEPHONE SUBSET

Ernest S. McLarn, Manhasset, N. Y., assignor to
International Standard Electric Corporation,
New York, N. Y., a corporation of Delaware

Application October 30, 1942, Serial No. 463,921

11 Claims. (Cl. 179—100)

This invention relates to a wall telephone subset. An object of the invention is the provision of a telephone subset of simplified construction which may be assembled and maintained at a minimum cost.

Another object of the invention is to provide a telephone subset in which any of the parts may be removed or replaced without using any tool other than a screw driver.

Still another object of the invention is the provision of a telephone instrument which can be manufactured in quantities from pre-tested parts, all of which are secured by screws as the instrument is being assembled, thereby preventing errors in assembling the instrument and eliminating the expense of final tests on the completed instrument.

A further object of the invention is the provision of a telephone instrument which may be maintained and installed by those having no great mechanical or electrical skill.

A further object of the invention is the provision of a telephone with a removable or hinged cover and having a contact assembly which can be inspected under normal operating conditions with the cover open or removed.

A still further object of the invention is the provision of a telephone subset assembly which may be used with different type covers, so that with one type of cover the assembly is adapted for use as a wall type telephone and with another type cover the same assembly may be used as a desk-type subset.

Other objects of the invention will appear in the following description given with the aid of the accompanying drawings of which

Fig. 1 shows in vertical section one embodiment of a wall telephone according to the present invention on a somewhat enlarged scale for the sake of clearness;

Fig. 2 is an enlarged view in elevation of the rear portion of the interior of the instrument shown in Fig. 1;

Fig. 3 is a top view on a reduced scale of the telephone subset with the cover closed;

Fig. 4 is a sectional view of the contact supporting pedestal on a reduced scale, the section being taken through 4—4 of Fig. 2;

Fig. 5 is a view of the interior of the contact pedestal with the cover and contact assembly removed; and

Fig. 6 shows the invention as applied to a desk set.

Referring to Figures 1 and 2: A flat metal sheet 10, provided with feet 11 forms a panel on

which the various parts of the instrument are mounted. Secured to panel 10, near the upper part thereof is a generally flat sub-panel 12 of molded material. A number of threaded bushings 13, Fig. 5, having soldering lugs 14 depending below the under surface of sub-panel 12 are positioned in the sub-panel during the molding process. On the upper surface of the sub-panel, a number of screws are shown in Fig. 2 which screw into the threaded portions of bushings 13. Of these screws, 15 and 16 fasten the lugs of a condenser unit 17, to pre-wired circuits under the sub-panel. Another screw, not shown passing through an opening in the opposite end of the condenser and threaded into panel 10 secures the condenser firmly in position.

Screws 18 and 19 are used to connect ringer 20 to the sub-panel circuits. Two other screws 21, Fig. 1, are used to attach the ringer to panel 10.

Screws 25, 26 and 27, 28 connect an induction coil unit 29 to the sub-panel circuits. Another screw, not shown is used to secure the opposite end of the induction coil unit to panel 10.

Screws 31, 32, 33, 34 are used to connect the terminals of a four wire cable, not shown, extending from the dial mechanism, Fig. 1, to the sub-panel circuits, while screw 35 and the clip 36 held thereby are used to support the cable.

Screws 40, 41, 42 and 43, 44, 45, are used for connecting telephone cords to the sub-panel. These cords may be of the tipped type in which case the screws are used to fasten the cord tips to the set, or they may be used to connect the so-called tipless cords and in this case the screws

are used to support a clamping block, not shown, provided with teeth which penetrate the insulation and make contact with the respective conductors of a parallel conductor cord. This arrangement is disclosed in applicant's application Serial Number 450,027, filed July 7, 1942.

Underneath sub-panel 12, the soldering lugs 14 depending from threaded bushings are interconnected by suitable conductors in the desired manner before the sub-panel is fastened to panel 10. Screws 50 and 51 are used to attach the sub-panel to panel 10.

At the lower central portion of the sub-panel 12, a generally hollow column or pedestal 52 is molded, which projects substantially perpendicularly from the flat portion of the sub-panel. The pedestal is slightly tapered. In Fig. 2, reference character 53 designates the line marking the junction of the base of the pedestal with the flat area of base 12 and line 54 indicates the edge of

the top of the pedestal which has a generally oblong-shaped outline.

Looking at the top and left sides of the pedestal, as shown in Fig. 2, these sides are completely closed by the molded material, while the lower side is entirely open and a portion of the right side is open extending downward from the bead 55 formed on the right side of the column perpendicular to the base. These open portions of the pedestal permit the installation and observation of the operation of cradle contacts described further on, in the interior of the pedestal.

The left side of the pedestal, as shown in Fig. 2 is provided with a raised bead 56 similar to 55 and in the same plane therewith. These beads are used to support a cover 57 of thin sheet metal provided with ridges 58 complementary to said beads and adapted to be snapped or sprung hereover. Cover 57 when in place completely encloses the open parts of the pedestal just described and serves to protect the enclosed parts against dust. The cover is held against longitudinal movement by the inner edge of the front of the pedestal which overlaps the metal cover as indicated by dotted lines in Fig. 2.

In Fig. 4 the pedestal is shown in section taken through the middle thereof looking from the left of Fig. 2 toward the right side of the drawings. This figure shows how the front and also the lower part of the right side of the pedestal is open below bead 55.

A group of cradle contacts 60 Fig. 1, in an insulating mounting 61 are secured by screws 62 to a metal stamping 63 which in turn is fastened to a thickened portion 65 of the interior of the pedestal by screws 66 which extend entirely through the pedestal via screw holes 67, Fig. 5, and are secured by nuts, not shown, on the upper surface of the pedestal. The oval-shaped recess, 68, Fig. 5 is to provide clearance for the ends of screws 62. The rear portions 69 of contacts 60 extend through an opening in sub-panel 12 where they are connected to desired circuits at the rear of the sub-panel.

One of the contacts 60 is provided with a pair of arms 70 which between them on a suitable spindle support a roller 71. This roller arrangement forms a convenient way for operating the contacts 60 from a cradle plunger 72 which engages roller 71 whenever the telephone hand set, not shown is, positioned in the cradle. This arrangement will be described further on.

Plunger 72 is formed with a flange 73 and a shoulder 74 and is free to reciprocate in a hole 75, Fig. 5, in the pedestal and a hole in a metallic bridge 76 secured to the pedestal by screws 77 and 78 which pass through holes 79 and 80, respectively, Fig. 5, in the pedestal. Spring 85 tends to hold flange 73 against the under surface of the bridge and holds the plunger 72 out of contact with roller 71 when the hand set is removed from the cradle causing these parts to assume the position shown in the drawings.

The section of plunger 72, beyond bridge 76 extends through a member 90 of novel use and construction which forms part of the outer case or enclosure of the subset instrument. Member 90 will be referred to again further on in the description.

The cover 91, Figs. 1 and 3, may have any suitable contour. In the present embodiment of the invention a cover is shown having pleasing symmetrical lines. Looking directly at the instrument, the cover has a generally oblong outline suggested by a section 92 extending outward

approximately perpendicular to the edge of panel 10, and forming part of the side portions of the cover. At the lower part of the cover, set-back section 93 is formed which tapers inwardly on three sides at 94 toward a front portion 95 in which an opening 96 is formed for dial mechanism 97.

The dial mechanism is detachably secured by screws 98, one of which is shown in Fig. 1 which are accessible from the interior of the cover. In the present embodiment the preferred form of dial mechanism is provided with a transparent casing through which the operation of the dial mechanism can be observed from the rear. Reference character 99, Fig. 1 indicates a transparent cover for a dial mechanism having such a transparent case. Cover 99 secured to cover 91 by screws 102, is provided with a turned over edge 100 which overlaps an annular ridge 101 formed on the inside of cover 91 to aid in excluding dust and moisture from the under surface of the dial mechanism, while the upper surface of the dial mechanism is similarly protected by annular gasket 103 disposed between the outer part of the dial mechanism and the outer surface of cover 91.

As previously stated, the dial mechanism of the present embodiment is provided with a four-wire flexible cable, not shown, having terminals which connect to the sub-panel circuits by screws 31, 32, 33 and 34, Fig. 2. It will be clear from the above description that dial mechanisms be interchanged quite easily with no tool other than a screw driver.

Alongside the edge of the dial, a thin area 104 is formed in the cover to provide a "knock out" hole through which a P. B. X button may be inserted if desired. A post 105 molded on the inner surface of casing 91 may be used as a support for the contacts operated by such P. B. X button.

Cover 91 flares outwardly beyond the area supporting the dial sufficiently to clear the front of pedestal 52 and immediately above this area the mid-section of the cover is formed with a slanting depression 111 which continues over the top of the cover until the edge thereof meets that of member 90. The cover is formed to fit closely about the curved edges of member 90, and both the cover and member 90 have the same general surface contour so that when the cover is in normal closed position, it is hardly noticeable that the top of the enclosure is formed of two separate members, 90 and 91.

The edge of member 90 is provided with a flange 112 which fits closely into a recess 113 formed in the under surface of cover 91, best shown in Figs. 1 and 2, which arrangement generally strengthens the enclosure and aids in excluding dust.

Member 90 preferably is detachably secured to panel 10 by means of screw 114, and is provided with a portion 115 which overlaps the edge of panel 10 as does the portion 116, Fig. 1 of cover 91.

Rising somewhat above the depressed central portion 111 at the top of cover 91 and on opposite sides thereof is a cradle for a handset formed by projections 120 and 121 on the right top part of the cover and similar portions 122 and 123 on the left top part as shown in Figs. 1 and 3. When a hand-set, not shown is resting in the cradle, plunger 72 will be depressed thereby, reversing the position of contacts 60 from that shown in the drawings.

Cover 91 may be fastened by any suitable means to panel 10. In the present embodiment

the casing is hinged to panel 10 by a simple arrangement consisting of a pair of metal strips 125, one of which is shown in Fig. 2 secured by screws, not shown, to bosses formed on the inside surface of casing 91. A pair of spaced slots 126, one of which is shown in Fig. 2 are provided in panel 10 to receive the respective metal strips 125 which are bent back toward the adjacent edge of panel 10 sufficiently to hold the strips in the slot. Near the opposite edge of panel 10 a slot, not shown, may be provided to receive any simple, catch device which will be effective to hold the cover securely in closed position. With the arrangement just described all parts including cover 81 of the wall telephone subset may be removed or replaced with no tool other than a screwdriver, and cover 91 may be easily opened and the parts therein including contacts 60 may be freely inspected while the telephone is in operating condition.

The arrangement possesses the important advantage that it may be readily converted from a wall set into a desk set with a few changes other than substituting a desk type cover for the wall type. This feature is important because a telephone plant department may keep on hand a number of dials and panel assemblies sufficient to meet anticipated requirements which may be for either wall telephones or desk sets. Plastic covers of the kind just described are relatively cheap, costing in quantities, less than fifty cents each, and a considerable number of each kind may be kept in stock at small expense and installed on the panel equipment just described according to requirements.

The wall set just described may be converted into a desk set by removing the wall type cover 91 and member 90. Referring now to Fig. 6: Plunger 72, bridge 76 and spring 85 are removed and the opening 75 in pedestal 52 for plunger 72 may be closed by suitable means, such as disc 130 secured to pedestal 52 by the same screws 77 and 78 which formerly held the bridge.

Referring to Fig. 4 it will be noted that a central opening 131-132 is formed in pedestal 52 which extends entirely through the pedestal. When used as a wall telephone opening 131 is closed by a pair of disc-shaped members 133 and 134 held together on opposite surfaces of bushing 135 by screw 136 Fig. 1, to exclude dust and moisture from the interior of the pedestal. In converting the wall type telephone to a desk set these discs and the associated screw are removed and a plunger 137 Fig. 6, is inserted in opening 131-132 where it is free to reciprocate in bushings 135 and 127. A washer 138 fastened to one end of the plunger by screw 139 limits the upward movement of the plunger due to spring 140 disposed on the plunger between flange 141 and the bottom surface of pedestal 52.

The plunger extends upward through desk type cover 142 and terminates in one button 143 or two buttons suitably spaced disposed within a handset cradle formed by projections 144, 145 and 146, 147. When a handset rests in the cradle, button 143 is depressed and cam surface 148 on plunger 137 engages and moves roller 71 toward the right of the drawing reversing the position of the contacts 60 from that shown. To keep the plunger from turning and thus displacing plunger-cam 148 relative to roller 71, plunger 137 is provided with a pair of axially disposed fins 149 which reciprocate in vertical slots 150, Fig. 2, in a substantially annular member 151 formed at the top of pedestal 52.

It is not thought necessary to describe the desk set shown in Figure 6 in detail as the parts are similar to those of the wall set already described and can be identified from the description already given.

Cover 142 of the desk set may be secured to panel 10 by screws 152 and bushings 153, or by the hinged arrangement described above in connection with the wall set. In the case of the desk set, the bottom of the set is always accessible for removing screws 152 while the hinged arrangement is usually more desirable in a wall set since panel 10 is invariably secured to a wall.

What is claimed is:

- 15 1. A wall telephone instrument comprising a panel adapted to be secured to a wall, a cover therefor having a cradle for a hand set formed thereon, a recess formed in said cover in the area of said cradle, a member secured to said panel, said member having a flanged edge adapted to fit into said recess, an opening in said member, a cradle plunger extending from the interior of said instrument through said opening adapted to be depressed when engaged by a hand set placed in said cradle.
- 20 2. A wall telephone instrument according to claim 1, in which said cover is removable and in which said cradle plunger remains in normal operating position with the cover removed.
- 25 3. A wall telephone instrument comprising a panel adapted to be secured to a wall, a member supported by said panel so as to project outwardly therefrom, said member having an opening therein and a flange at one of its edges, a cradle plunger extending from the interior of the instrument outwardly toward the exterior thereof through said opening, a cover for said instrument having an opening extending from an edge thereof through which said cradle plunger projects whereby said cover may be removed to permit inspection of the interior of the instrument under normal operating conditions, said edge of the cover having a recess adapted to receive the flange of said member.
- 30 4. A wall telephone instrument comprising a panel adapted to be secured to a wall, a member projecting outwardly from said panel and secured thereto provided with an opening, a cradle plunger extending from the interior of said instrument outwardly to the exterior thereof through said opening, a cover for said instrument having an edge portion provided with a recess shaped to fit around at least a part of said member where said member cooperates with said cover in forming an enclosure for said instrument.
- 35 5. A wall telephone according to claim 4 in which said cover is hinged whereby the cover may be swung open without disturbing said member or the cradle plunger extending therethrough.
- 40 6. A wall telephone according to claim 4 in which said member is of a generally flat shape and formed with a contour similar to the adjacent portions of said cover and forms a part of the enclosure for said instrument when the cover is in closed position.
- 45 7. A wall telephone according to claim 4 in which said cover is hinged to said panel, and in which said member has a generally flat surface shaped to conform to that of the adjacent portions of said cover and having curved edges, and in which said recess in said cover is formed to fit closely around said curved edges.
- 50 8. A wall telephone according to claim 4 in which said cover is hinged to said panel, and in

which said member has curved edges and a generally flat surface shaped to conform to that of adjacent portions of said cover and in which said recess in said cover is formed to fit closely around said curved edges of said member, the shape of said curved edges being such as to permit the cover to be freely opened and closed and when closed the edges of said recess fit closely about the curved edges of said member.

9. A telephone subset assembly adapted to be used in connection with wall type and desk type telephones comprising a panel, a pedestal supported by said panel, a set of cradle contacts supported by said pedestal, an opening in the top of said pedestal for receiving a cradle plunger for operating said contacts when said assembly is used as desk telephone, and an opening in one side of said pedestal to receive a plunger when the assembly is used as a wall-type telephone.

10. A telephone subset assembly according to claim 9 in which a sub-panel of molded material is secured to said panel, said pedestal being formed integrally with said sub-panel, and wherein when said assembly is used as a wall-type tele-

phone, a member provided with a hole is secured to said panel with said hole in register with said opening in one side of said pedestal, said member forming part of an enclosure for said assembly, a portion of the second mentioned plunger extending through said hole whereby said plunger may be operated from the exterior of said member.

11. A telephone subset assembly according to claim 9 in which a sub-panel of molded material is secured to said panel, said pedestal being formed integrally with said sub-panel, and wherein when said assembly is used as a wall-type telephone, a member provided with a hole is secured to said panel with said hole in register with said opening in one side of said pedestal, said member forming part of the enclosure for said assembly, a portion of the second mentioned plunger extending through said hole to make possible the operation thereof from the exterior of said member, said member being adapted to be removed from said panel when said assembly is changed from a wall type to a desk type set.

ERNEST S. McLARN.
